Primary Examiner — Kimberly Barnes

(74) Attorney, Agent, or Firm — Warner Norcross + Judd LLP

(57) CLAIM

The ornamental design for a portable carpet cleaner, as shown and described.

DESCRIPTION

FIG. 1 is a front perspective view of a portable carpet cleaner showing my new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.
